UNITED STATES PATENT OFFICE

165,058

ADJUSTABLE METAL COUCH CHAIR

Simon Deutsch, Miami Beach, Fla.

Application May 25, 1950, Serial No. 10,164

Term of patent 14 years

(Cl. D15—1)

To all whom it may concern:

Be it known that I, Simon Deutsch, a citizen of the United States, residing at Miami Beach, in the county of Dade and State of Florida, have invented a new, original, and ornamental Design for an Adjustable Metal Couch Chair, of which the following is a specification, reference being had to the accompanying drawing, forming a part thereof.

Figure 1 is a perspective view of an adjustable metal couch chair showing my new design,

Figure 2 is a side elevation thereof and,

Figure 3 is a front elevation thereof.

I claim:

The ornamental design for an adjustable metal couch chair, as shown.

SIMON DEUTSCH,
